UNITED STATES PATENT OFFICE.

ETHEL D. BURTCBY, OF TULSA, OKLAHOMA.

COMBINED CORSET ANCHOR AND HOSE SUPPORTER.

Application filed December 17, 1923. Serial No. 681,208.

To all whom it may concern:

Be it known that ETHEL D. BURTCBY, citizen of the United States, residing at Tulsa, in the county of Tulsa and State 5 of Oklahoma, has invented certain new and useful Improvements in Combined Corset Anchors and Hose Supporters, of which the following is a specification.

This invention relates to new and useful 10 improvements in a combined corset anchor and hose supporter.

Heretofore attempts have been made to provide a device for retaining the corset against upward movement and also for supporting the hose. These attempts have been 15 unsatisfactory because the limb-encircling band to which the corset was connected, interfered with the blood circulation in the limb or because the strap connecting the 20 corset with the band was located in front of the knee and consequently interfered with the free movement of the limb either when the wearer was walking or sitting.

The principal object of my invention is 25 to provide a combined corset anchor and hose supporter which will not interfere with the blood circulation in the limb, will not interfere with the free movement of the limb when the wearer is either walking or 30 sitting, and which will support the hose from the corset with a minimum amount of strain exerted on the hose.

Another object of the invention is to provide the limb-encircling band with means 35 located at the front for adjusting the length of said band whereby ready access to the same may be had and the adjustment made with a minimum amount of labor and time.

A further object of the invention is to 40 provide a device of the character described which is simple in construction and is, therefore, cheap to manufacture.

With the above and other objects in view which will more readily appear as the 45 nature of the invention is better understood, the same consists in the novel construction, combination and arrangement of parts hereinafter more fully described, illustrated and claimed.

50 In the accompanying drawing which shows one form of my invention.

Figure 1 is a side elevation showing the application of my invention.

Figure 2 is a similar view, the hose, however, being removed to better disclose the 55 limb-encircling band and its connection

with the corset and brassière anchor straps.

Figure 3 is a plan view of the limb-encircling band, and

Figure 4 is a detail view showing the 60 means for adjusting the band.

Like reference numerals designate corresponding parts in all the figures of the drawing.

Referring to the drawing, A designates 65 the body of a person, B one of the limbs, C a brassière, D a corset, and E a hose.

In order to provide means for anchoring the corset and brassière against upward 70 movement, I have provided a limb-encircling band F which is positioned below the knee and is connected to the corset and brassière in such a manner that there will be no interference with the blood circulation in the limb nor any interference with the 75 movement of the limb when the wearer is either walking or sitting. This band F is an open ended band and consists in a length 5 of elastic material having at one end a metallic loop 6 containing an eye 7. The 80

band F intermediate its ends is provided with means 8 for adjusting the length thereof. The other end of the band F has attached thereto a tab 9 which is preferably 85 formed of inelastic material and is preferably hexagonal in shape. The tab includes an upper edge 10 which is disposed at an acute angle to the longitudinal axis of the length 5 and extending upwardly at an obtuse angle to said longitudinal axis of the 90

length 5 is a pair of wire loops 11 and 12 respectively, said loops being secured to the tab by means of cloth loops 13 and 14 respectively, said cloth loops in turn being secured to the tab 9 by suitable stitching. 95

The longitudinal axis of the length 5 is indicated by the line $x-x$ and the inclined plane containing the wire loops 11 and 12 is indicated by the line $y-y$. Secured to the outer face of the tab 9 by stitching or the 100 like is a button 15 for engagement with the eye 7.

A corset anchor strap 16 is secured at its upper end to one side of the corset, and is provided at its lower end with a button 17. 105 The limb-encircling band F is positioned below the knee 18 of the wearer and the tab 9 is disposed at the side of the knee and directly under the point of attachment of the upper end of the anchor strap 16. This 110 positions the adjusting means 8 in advance of the tab 9 whereby ready access may be

had to said adjusting means and the length of the band adjusted with a minimum amount of labor. It will thus be seen that when the band F is connected to the corset through the medium of the strap 16, there is a tendency to exert an upward pull on the band and a downward pull on the corset. Thus the end portions of the band F on opposite sides of the vertically disposed anchor strap 16 are arranged at obtuse angles relative to the vertical plane of the strap, and consequently there is no interference with the blood circulation in the limb. Furthermore, by positioning the strap 16 at the side of the corset there is no interference of the movements of the limb when the wearer is either walking or sitting. In order to retain the brassière against upward movement I have provided the latter with a depending anchoring strap 19 having a button 20 at its lower end for engagement with the loop 11. The limb-encircling band F is preferably worn under the hose E, and in order to support the latter, I have provided the corset with a pair of depending straps 21 and 22 respectively, said straps being shorter than and disposed on opposite sides of the corset anchoring strap 16. The lower end of these straps 21 and 22 are provided with the usual hose engaging loop and button fasteners 23 and 24.

From the foregoing, it will be observed that the upward pull of the corset is prevented by the limb-encircling band F and the connecting anchor strap 16, and consequently the strain in supporting the hose from the corset is reduced to a minimum and the life of the hose is correspondingly increased as a result. It will also be observed that I have provided a corset anchor of extremely simple construction, the same consisting of but two parts, (1) a limb-encircling band, and (2) an anchor strap. The anchor strap extends vertically and is disposed at the medial line at the side of the wearer. By providing the pivotal connection 17 between the strap and the band, and a pivotal connection 15 between the ends of the band, I have provided an article which will retain the corset against upward movement in different positions assumed by the wearer and without affecting any discomfort to the wearer. The band is so constructed that in its relation to the strap, the strap and each adjacent portion of the band are disposed at an obtuse angle. This is very important in that it provides a band

which avoids stoppage of blood circulation in the limb of the wearer.

It is also to be noted that the strap is connected to the lower portion of the corset whereas the anchoring strap for the brassière is connected to the latter and necessarily extends above the point of connection between the corset anchor strap and the corset. Thus when the wearer bends forwardly the brassière anchor strap will be flexed, but the corset anchor strap will be unaffected. It is also noted that the corset anchor strap and the brassière anchor strap are connected at their lower ends to one end of the single limb-encircling band.

I claim:

1. The combination with a corset, of a single open-ended limb-encircling band adapted to be positioned on the wearer below the knee, said band including a detachable pivotal connection between its ends, and a vertically disposed anchor strap for the corset arranged at the medial line of the side of the wearer and secured at its upper end to the corset and directly connected at its lower end to the band by a pivotal connection located at a point above said band connection. 85

2. The combination with a corset, of a single open-ended limb-encircling band adapted to be positioned on the wearer below the knee, said band including a detachable pivotal connection between its ends, and a vertically disposed anchor strap for the corset arranged at the medial line of the side of the wearer and secured at its upper end to the corset and directly connected at its lower end to the band by a pivotal connection located at a point above said band connection, the strap and each adjacent portion of band being disposed at an obtuse angle. 90

3. The combination with a corset, of a brassière, a limb-encircling band adapted to be positioned on the wearer below the knee, a vertically disposed anchor strap for the corset arranged at the medial line of the side of the wearer and secured at its upper end to the lower portion of the corset and at its lower end to said band, and a vertically disposed anchor strap for the brassière disposed in advance of the corset anchor strap and connected at its upper end to the brassière and at its lower end to said band. 105 110

In testimony whereof I hereunto affix my signature.

ETHEL D. BURTCHBY.
